UNITED STATES PATENT OFFICE.

HERMAN WIEDEMAN, OF CHICAGO, ILLINOIS, ASSIGNOR TO J. S. McDONALD COMPANY, OF CHICAGO, ILLINOIS, A CORPORATION OF ILLINOIS.

LOCK FOR LOOSE-LEAF BINDERS.

SPECIFICATION forming part of Letters Patent No. 782,939, dated February 21, 1905.

Application filed November 7, 1904. Serial No. 231,752.

To all whom it may concern:

Be it known that I, HERMAN WIEDEMAN, a citizen of the United States, and a resident of Chicago, in the county of Cook and State of Illinois, have invented certain new and useful Improvements in Locks for Loose-Leaf Binders, of which the following is a full, clear, and exact description.

My invention relates to that class of binders known as the "loose-leaf system," by which the leaves of ledgers, account-books, bill-books, &c., are temporarily held in proper relation to each other in book form and locked by clamping means contained within one of the covers of said book.

My improvement is especially directed to the lock by which the covers of said book are securely held in a locked position to retain the loose leaves.

It is the object of my invention to provide a readily-separated and efficient lock by means of which the covers are securely held, by simply turning a key, in a clamped position when locked, and when unlocked the clamping-jaws of the same will automatically return to a normally unlocked position. This I accomplish by the means hereinafter fully described in the specification and as particularly pointed out in the claims.

In the drawings, Figure 1 is a plan view of the lock embodying my invention, having the top plate of the case removed therefrom. Fig. 2 is a longitudinal vertical section through said lock, taken on line 2 2, Fig. 1, showing the same in connection with a book. Fig. 3 is a transverse section on line 3 3, Fig. 1, showing the method of operating the cam.

Most of the loose-leaf books now on the market consist of upper and lower clamping-plates A and B, each having a hinged cover secured thereto. The lower clamping-plate B has one or more tubes or studs b b arising at right angles therefrom that pass through suitable alining openings a in the upper plate A. When the desired number of loose leaves have been inserted in the book, the same is placed on its back and compressed by the operator and then by turning a key locked by

the mechanism housed within the casing forming the upper clamping-plate A. This mechanism comprises a pair of locking-jaws C C, arranged longitudinally within the casing, one on one side of the center of length of the same and the other on the other side. These jaws are pivoted mediate their ends and have their attenuated ends c c extend longitudinally past the operating-cam D, which latter will be hereinafter more fully described. The opposite ends of these locking-jaws extend toward the side edges of the book just past the studs b b and are enlarged sufficiently to permit the cutting of circular recesses c' c' in their engaging edges, which conform in curvature to that portion of the exterior of said studs with which they come in contact. The operating-cam D, above referred to, is preferably rectangular in shape, with two of its diagonally opposite corners rounded slightly and has projecting from each face a pivotal stud d, adapted to be seated in suitable alining openings in the case and cover for housing the mechanism. A suitable key E, provided with a square depending shank, operates this cam by entering the square opening in the center thereof. In order to keep the locking-jaws C C normally out of engagement with the studs b b, a curved bow-spring F is inserted between the upturned sides of the housing in such position that one extremity impinges and presses against the edges of said jaws mediate the recessed end thereof, and its pivot and the other extremity presses against the sides of the casing.

In operation after the loose leaves are inserted between the clamping-plates the latter are compressed as tightly as possible, and the cam operated by the key is turned to the right, whereupon the attenuated ends of the locking-jaws will be forced apart and the recesses at the opposite ends will engage the vertical studs, thereby locking the two covers rigidly in position. The flat portions of the narrow end of the cam coming into engagement with the ends of the locking-jaws prevent the latter from slipping back when locked; but when said cam is turned back

the springs press the jaws away from the studs and automatically return the mechanism to normal position.

What I claim as new is—

- 5 1. A lock for loose-leaf binders consisting of upper and lower clamping-plates; studs arising from said lower plate; openings in said upper plate through which said studs pass; and means for locking said plates comprising an elongated cam, pivoted locking-jaws having reduced end portions that engage and are operated by said cam, semicircular recesses in the opposite end of said jaws that conform in curvature with and engage said 10 studs, and bow-springs for retaining said jaws normally out of engagement with said studs, said springs engaging said jaws at one extremity and the upturned edge of the clamping-plate at the other extremity, at a point beyond said recess, and the intermediate portion bearing against the opposite upturned portion of said clamping-plate.
- 15 2. A lock for loose-leaf binders consisting of an upper hollow clamping-plate and a lower clamping-plate; studs arising from said

lower plate; openings in said upper plate in alignment with and through which said studs pass; and means for locking said plates comprising a pivoted elongated cam, locking-jaws pivoted mediate their ends, having reduced end portions that engage and are operated by said cam, semicircular recesses in the opposite end of said jaws that conform in curvature with and engage said studs, and bow-springs one extremity of which engages 30 said jaws mediate their pivots and said recesses which bears against the side flange of the upper plate mediate its extremities and has its other extremity engage the sides of the upper plate beyond the extremity of the 35 locking-jaw for retaining said jaws normally out of engagement with said studs.

In testimony whereof I have hereunto set my hand this 1st day of November, A. D. 1904.

HERMAN WIEDEMAN.
